OF WASHINGTON.

DOOR-FASTENER.

1,211,711.

Specification of Letters Patent.

Patented Jan. 9, 1917.

Application filed August 7, 1916. Serial No. 113,492.

To all whom it may concern:

Be it known that we, HOMER V. JUNGST and HARRY G. KENNEDY, citizens of the United States, residing at Seattle, in the 5 county of King and State of Washington, have invented certain new and useful Improvements in Door-Fasteners, of which the following is a specification.

This invention relates to that class of door 10 fasteners known as hasps; and its object is the improvement of devices of this character for securing a door in a more firm condition when fastened and enable the door or doors to which the invention is applied to be 15 quickly secured or released.

The invention is especially adapted for use on doors of the bodies of vehicles, such as are employed in the delivery of merchandise, and will serve to prevent rattling of 20 the doors with a consequent increase in the durability and efficiency of the latter.

The invention consists in the novel construction, adaptation and combination of parts as will be hereinafter described and 25 claimed.

In the accompanying drawings:—Figure 1 is a front elevational view of our improved hasp fastener applied to a pair of doors; Fig. 2 is a horizontal section through 2—2 30 of Fig. 1; Fig. 3 and Fig. 4 are detail vertical views to enlarged scales, through 3—3 and 4—4 of Fig. 1; and Fig. 5 is a perspective view of the spring element shown detached.

35 The reference numeral 6 represents a frame for an opening as at the rear end of an auto delivery car.

A pair of doors designated by 7 and 8 are connected to said frame by hinges 9 and 40 at the meeting ends, one of the doors, as 8, is provided with a protruding strip 10 adapted to overlap the other door. According to the present invention, a staple 26 provided on one of the doors is engageable by 45 a cam element of a locking bar 20 which is pivotally connected to the other of said doors. The supporting member 11, or spring member as it will be hereinafter designated, is formed with a loop 12 at one end to receive a pivotal supporting staple 15 and has 50 an outwardly bowed portion 18 adjacent to the other end 19. The portion at or near the end 19 is made flat and in alinement with

a flat portion 17 at the other side of the bowed part 18. The latter, as best shown in 55 Fig. 3, tapers on its outer side to a relatively sharp edge at the top. Between the part 18 and the looped end 12, the spring member has a portion 13 projecting in front of the part 17 and terminating in an inclined 60 shoulder 14. The length of the spring member is sufficient to have the end 19 lie against the cleat or strip 10 when in the position in which it is shown by full lines in Fig. 2. A shoulder 16 is provided in the loop so as 65 to engage against the staple 15 to prevent the parts 11 and 20 being swung farther back than that in which the referred to parts are indicated by broken lines 11¹ and 20¹ in Fig. 2.

The lock bar 20 is pivoted to the flat portion 17 of the member 11 by means of a headed pin 21 and is provided with an inclined end 22 adapted to engage with the inclined shoulder 14 of said member to prevent 70 the lock bar from dropping down below the horizontal. The lock bar 20 may be provided with a curved portion 23 engageable with the bowed portion 18 of the spring member, and terminates in a handle 24 from 75 which extends a downwardly directed cam shaped locking element 25 that is adapted to engage within the staple 26 of door 8. The bar 20 and the locking element 25 serve as a hook which is releasably secured by the locking or bill element engaging, as explained, 80 in the staple and may be provided with a hole 27 to receive a padlock (not shown).

In order that the lockbar will not interfere with the member 11 when the former is 90 lowered into engaging position, the contact portion 18 and tip 19 of the spring member 11 are preferably tapered toward the upper edge thereof, see Fig. 3. When in use the device presents the appearance shown in 95 Fig. 1. When the doors are to be opened, the operator grasps the handle 24 raises the lock bar 20 into a position as indicated by broken lines in Fig. 1, and then turns the hasp back into position shown by broken 100 lines in Fig. 2. The hasp is brought into operative position by turning it inwardly until the top of the spring member 11 rests on the cleat 10, then forcing the cam shaped element 25 downwardly into the staple 26 to 105 exercise a rearward thrust against the

spring to secure the door or doors. When in the closed position, it is to be noted that the curved portion 23 of the lock bar maintains a pressure on the contact portion 18 of 5 the spring element and the tip 19 of the latter is held firmly in contact with the cleat 10, thus rigidly holding the doors 7 and 8 closed and preventing rattling and consequent wear due to relative movement be- 10 tween the doors.

Obviously the device would operate in practically the same manner if a rigid support were substituted in place of either of the doors.

15 What we claim and desire to secure by Letters Patent, is—

1. A hasp fastener comprising a spring member adapted to be pivotally connected with a door, a lock bar pivoted to said 20 spring member, and means for detachably connecting said lock bar with another door and impart a pressure which will be exerted through the medium of said spring member on said doors.

25 2. A hasp fastener comprising a spring member adapted to be pivotally secured from one end thereof to a door and having a tip portion adapted to engage with and press against the door, a lock bar pivotally 30 connected to said spring member and engageable with the latter intermediate its length, a locking element provided on the outer end of said bar, and means engageable by said locking element to exert a pressure 35 through the medium of said spring member for securing the door in its closed position.

3. A hasp fastener comprising a spring member adapted to be hingedly secured to a door, said spring member being provided 40 with a shoulder engageable with said staple to limit the horizontal movement of said spring member with respect to said door, a locking bar pivoted to said spring member, and means for engaging said locking bar in 45 a support.

4. A hasp fastener comprising a spring member having a curved central portion, a locking bar pivotally secured to said spring member and at one side of said curved portion, a locking element on the outer side thereof, and means engageable with said locking element to cause the locking bar to 50 exercise a lateral thrust against the curved portion of said spring member.

55 5. A hasp fastener comprising a spring

member having a curved central portion, an inclined shoulder provided on said spring member, a locking bar pivotally secured at one end to said spring member and having an inclined end adapted to engage the afore- 60 said shoulder to limit the downward movement thereof, a lock element on the outer end of said bar, and means engageable with the lock element.

6. The combination with a pair of swing- 65 ing doors, of a spring member hingedly connected to one of said doors to swing in a plane at right angles thereto, said spring member being curved outwardly to form a contact portion and terminating in a door 70 engaging tip portion, means for limiting the swinging movement of said spring member with respect to the associated door, a lock bar pivotally secured to said spring member and having a lock element on its 75 outer end and means secured to the other of said doors and engageable with the lock element for rendering said spring member operative to secure both doors.

7. In combination with a door, of a hasp 80 fastener comprising locking member and a spring member connected together for relative vertical movements, said locking member being provided at its free end with a cam shaped element, means for hingedly 85 supporting said spring member to enable the latter to be swung with the locking member in a horizontal direction, and means engageable by the aforesaid cam element whereby the spring element is caused to 90 press against the door.

8. A hasp fastener comprising a spring member hingedly connected to a support for substantially horizontal movements, a locking member pivotally connected to the 95 spring member for relative movements in a substantially vertical direction, said locking member being provided with a hook portion, and means engageable by said hook while the locking member is being swung 100 down to afford a horizontal thrust against said spring member.

Signed at Seattle, Washington, this 27th day of July, 1916.

HOMER V. JUNGST.
HARRY G. KENNEDY.
